(57) **CLAIM**

The ornamental design for an “LED lens,” as shown and described.

DESCRIPTION

FIG. 1 is a perspective view of embodiment one of the LED lens;

FIG. 2 is a front view of embodiment one of the LED lens;
FIG. 3 is a rear view of embodiment one of the LED lens;
FIG. 4 is a left side view of embodiment one of the LED lens;
FIG. 5 is a right side view of embodiment one of the LED lens;
FIG. 6 is a top view of embodiment one of the LED lens; and
FIG. 7 is a bottom view of embodiment one of the LED lens.

FIG. 8 is a perspective view of embodiment two of the LED lens;

FIG. 9 is a front view of embodiment two of the LED lens;
FIG. 10 is a rear view of embodiment two of the LED lens;
FIG. 11 is a left side view of embodiment two of the LED lens;
FIG. 12 is a right side view of embodiment two of the LED lens;

FIG. 13 is a top view of embodiment two of the LED lens;
and,

FIG. 14 is a bottom view of embodiment two of the LED lens.
